No. 616,950.

Patented Jan. 3, 1899.

T. H. MAYTAG.
WINDOW SHADE EXHIBITOR AND PROTECTOR.

(Application filed June 4, 1897.)

(No Model.)

UNITED STATES PATENT OFFICE.

THEODORE H. MAYTAG, OF LAUREL, IOWA.

WINDOW-SHADE EXHIBITOR AND PROTECTOR.

SPECIFICATION forming part of Letters Patent No. 616,950, dated January 3, 1899.

Application filed June 4, 1897. Serial No. 639,424. (No model.)

To all whom it may concern:

Be it known that I, THEODORE H. MAYTAG, a citizen of the United States, residing at Laurel, in the county of Marshall and State of Iowa, have invented a new and useful Window-Shade Exhibitor and Protector, of which the following is a specification.

My object is to provide an improved case adapted for concealing and protecting window-curtains and for suspending and displaying and interchangeably and detachably connecting curtains therewith at pleasure.

My invention consists in the construction, arrangement, and combination of the various parts of the device whereby the objects contemplated are attained, as hereinafter more fully set forth, pointed out in my claims, and illustrated in the accompanying drawings, in which—

20 Figure 1 shows a transverse sectional view of the holder or case. Fig. 2 shows a front elevation of the complete device with parts broken away to show certain features of internal construction and also showing a number of curtains therein partly drawn downwardly and detachably and interchangeably connected therewith. Fig. 3 shows an end elevation of the device and by dotted lines a changed position thereof.

25 The case is composed of two parts, each being semicircular in cross-section and preferably made of sheet metal and hinged together at their upper ends by means of the compass-joints 12, which are formed on the end pieces.

30 11. Shoulders 13 are provided, whereby the movement of the compass-joint is restricted to a half-circle, as clearly illustrated by the dotted lines in Fig. 3. Hence when the casing is opened to its full limit the straight edges of the ends will be at the bottom and will be extended in a horizontal plane.

35 Fixed to the interior of each end portion, near its straight edge, is a plate 14, provided with a series of inclined open slots 15, of such size and shape as to admit the journals on the ends of a curtain-roller.

40 The reference-numeral 16 is used to indicate a plate having a series of openings 17 therein. A similar plate is attached to each 45 section of each end by means of a screw 18 a

considerable distance below the center of the said end piece, and said plate is projected from the center of the plate outwardly.

45 The reference-numeral 19 indicates a rod or hanger device having a hook 20 at its upper end, whereby it may be detachably fixed to an elevated support, such as 21, and 22 indicates a screw passed through an eye in the lower end of the rod 19 into one of the openings 17 in the plate 16. 60

55 In practical use the device is suspended by means of the four rods 19, and a number of window-curtains or other merchandise to be displayed are detachably and interchangeably placed in the mating parts of the case 65 by having the journals on the ends of the curtains inserted in the inclined open slots 15. These two rows of curtains are held within the casing and securely protected against dust and exposure. When it is desired to display 70 the curtains, the parts of the casing are grasped and separated, whereupon the casing will assume the position shown by dotted lines in Fig. 3, and inasmuch as the rods 19 are attached to the sides beyond the dead-center 75 of each a preponderance of weight will be on the hinged edges of the hemispheres, and hence the casing will be held in this position.

80 It is obvious that by moving the point of attachment of the rods 19 relative to the plates 16 it will require more or less power to open or close the casing. However, in either of the positions which this point of attachment is capable of assuming the casing will be held in either its open or its closed position when 85 placed therein.

85 Having thus described my invention, what I claim as new therein, and desire to secure by Letters Patent of the United States therefore, is— 90

95 1. In a case for protecting and displaying curtains and consisting of two mating semicylindrical parts hinged together, mating plates having inclined open slots fixed to the inside faces and straight edge portions of the 95 ends of the case for detachably and interchangeably connecting curtains therewith, plates having a plurality of openings fixed to the outside faces of said semicylindrical parts and hangers adapted to be adjustably con- 100

nected with said plates, arranged and combined to operate in the manner set forth for the purposes stated.

2. A case for protecting and displaying curtains comprising a case composed of two mating semicylindrical parts hinged together, plates having inclined open slots fixed to the straight edges of the ends of the said mating parts of the case, plates having a plurality of screw-seats fixed to the outside faces of the said ends to extend at right angles to the

straight edges of the said ends, rods having hooks at their upper ends and eyes at their lower ends, and screws for connecting the eyes of the rods with the plates having screw-seats, all arranged and combined to operate in the manner set forth for the purposes stated. 15

THEODORE H. MAYTAG.
